UNITED STATES PATENT OFFICE.

FREDERICK JAMES REES, OF LONDON, ENGLAND.

WINDOW OF ROAD VEHICLES.

1,420,617.

Specification of Letters Patent. Patented June 20, 1922.

Application filed March 28, 1922. Serial No. 547,522.

To all whom it may concern:

Be it known that FREDERICK JAMES REES, a subject of the King of Great Britain, residing at London, England, has invented certain new and useful Improvements in Connection with the Windows of Road Vehicles, of which the following is a specification.

This invention relates to that class of window fittings for motor road vehicles in which the grooved runners are provided in the body and doors with folding grooved runners at the top part of the door which folding runners can be positioned vertically so that a window positioned within the grooved runners in the body or door can be raised and held between the folding runners and when lowered into the fixed runners the folded runners can be folded on to the window either in the same plane or one upon the other.

Now the object of this invention is to construct such fittings for the windows of road vehicles and especially those using a collapsible hood in an improved manner and whereby the usual folding mid pillars are dispensed with.

My invention comprises a window fitting for road vehicles consisting of two U shaped runners, closed or not at the bottom and fitted within the door or side on opposite sides, plates having a bearing piece or quadrant slots at the upper end of each U shaped runner, a U shaped folding runner pivoted to each pair of plates, a nose piece on each folding runner next to the pivotal points and having a shaped portion to rest upon the bearers of the plates or pins to ride in the quadrant slots one folding runner being pivoted at a lower level than the other, the folding runners being placed each in line with the other runners to allow of a window situated in the runners being closed and folded one on top of the other when the window is open.

My invention will be clearly understood from the following description aided by the annexed drawings in which—

Figure 1 is a side elevation of a portion of the side of a vehicle with part broken away and showing the windows closed.

Figure 2 is a plan of Figure 1.

Figure 3 is a similar view to Figure 1 but showing the window open.

Figure 4 is a plan of the left hand side 55 of Figure 3.

Figure 5 is a plan on an enlarged scale of one U runner and one folding U runner and the plate and showing the bearings for the folding U runner.

For the purpose of my invention I make each half fitting 1 from a U shaped runner of metal having the side walls of equal depth or one of greater depth than the other and at the upper end I secure or form one or two plates 2, 2, preferably two, one on either side such plates 2, 2, carrying a bearing 3 and a bearing piece 4 between them or it may be a quadrant slot. These runners 1 are of a length to receive more than the window 5 and are closed in at the bottom 6 to hold the window 5, and are preferably received within a window-receiving cavity in the body of the vehicle.

To each plate 2 in the bearings 3 is pivoted another U shaped folding runner 7, each folding runner having a projecting nose piece 8 at its pivotal end which when the runners 7 are folded down abut against the bearing piece 4 whereby the runners 7 are held in the horizontal position. The bearings 3 are preferably so positioned within the cavities below the mouth thereof a sufficient distance so that the runners 7 when folded will lie entirely within said cavities, the window being preferably of such dimensions as to be adapted, when received within the cavity, to be spaced from the mouth thereof.

Two of these runners 1 are screwed to the inside of a door with the folding runners 7 when opened out projecting therefrom and to these runners 1 may be screwed the frame carrying the usual padding and fence plate the usual garnish rail being outside the door or such runners may be secured to the body 95 of the vehicle in the same way.

In vehicles wholly enclosed by a hood and windows the door 9 or doors may be provided with my appliance and also the sides 10 and the folding runners may also be formed to assist in carrying the hood, that is to say the front posts 8^a carrying the front glass may be affixed as is usual and my appliances may be affixed to a door 9 and the body on opposite sides of the driver's 105 seat and the door and body on opposite sides of the rear seats and in this case on one side when the folding runners 7 are opened out those on the door or body will abut against the front pillar 8^a as in Figure 1 whilst 110

those at the rear of the door 9 and the front of the side window or rear door will abut against each other as at Figure 1 and those at the back of the side 10 or rear door will 5 abut against the hood pillar or support 11 and the hoop sticks or the folding member can be engaged with the free ends of the folding runner not employed on a door to hold them in position the ends of such folding runners being shaped accordingly.

As will be understood the windows, whether of all glass or framed, can be raised and lowered in the runners 1 and when lowered the folding runners 7 are folded 15 down upon one another as in Figure 3 so as to leave the top of the door 9 or the side 10 perfectly free and to allow of the folding runners 7 lying level I hinge one at a lower level than the other for each pair, the nose 20 piece 8 resting on the bearing piece 4 or the slots riding on the pins until the other ends of the quadrant are reached when the folding runners will be held properly, and to ensure a more solid resistance to the runners 25 1 carrying the lower pivoted folding runners 7 I may form its bearing piece 4 with a nose 4^a against which the end 8^b on nose piece 8 rests when the runner is lowered the higher pivoted runner 7 resting on the 30 lower pivoted runner 7 obviates the use of the nose 4^a on the runner 1 on the other side of the window.

Each half fitting may be connected at the bottom by a U strip 12 if desired.

What I do claim as my invention and desire to secure by Letters Patent is:—

1. A window fitting for vehicles, comprising U-shaped runners adapted to fit between the walls of the pockets in the vehicle body, plates at the upper end of said runners having bearing pieces thereon, foldable U-shaped runners pivoted to the upper end of said first named runners and having portions thereof adjacent the pivot shaped to rest against said bearing pieces when the pivoted runners are 40 folded, whereby the foldable runners may be supported in a horizontal position between the pocket walls.

2. In a vehicle having window-receiving cavities, U-shaped runners within said cavities and windows adapted when received within said cavities to be spaced a distance from the mouths of the cavities, U-shaped foldable runners pivoted to said first named runners below the mouth of said cavity, triangular bearing pieces on said first named runners and triangular nose pieces on said foldable runners adapted to fit against the bearing pieces to maintain the foldable runners in horizontal position independently of 55 other support when folded within the cavity.

In testimony whereof I have hereunto set my hand.

FREDERICK JAMES REES.
